UNITED STATES PATENT OFFICE

JAMES I. BENJAMIN, OF LAWRENCE, MASSACHUSETTS, ASSIGNOR TO PILOT RADIO AND TUBE CORPORATION, OF LAWRENCE, MASSACHUSETTS, A CORPORATION OF DELAWARE

DESIGN FOR A CABINET FOR RADIO RECEIVERS

Application filed September 29, 1931. Serial No. 41,255. Term of patent 3½ years.

To all whom it may concern:

Be it known that JAMES I. BENJAMIN, a citizen of the United States, residing in the city of Lawrence, in the Commonwealth of Massachusetts, county of Essex, has invented a new, original, and ornamental Design for a Cabinet for Radio Receivers, of which the following is a specification, reference being had to the accompanying drawings, forming part thereof, in which:

Figure 1 represents a perspective view of the cabinet for radio receivers, and

Figure 2 represents a plan view of the top of said cabinet for radio receivers.

The side of the cabinet for radio receivers, not shown in the drawings, is the same in all details as the side disclosed in the drawings, with the exception of the switch, which is omitted.

The rear of the cabinet for radio receivers is open.

I claim:

The ornamental design for a cabinet for radio receivers, as shown and described.

JAMES I. BENJAMIN
